(57) **CLAIM**

The ornamental design for a protective cover with kickstands for tablet, as shown and described.

DESCRIPTION

FIG. 1 is a front perspective view of a protective cover with kickstands for tablet showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear perspective view of the protective cover with kickstands for tablet showing the kickstands in an open state; and,

FIG. 10 is a front perspective view of the protective cover with kickstands for tablet showing the kickstands in an open state in the environment of a tablet.

The dash-dash broken lines illustrate portions of the protective cover with kickstands for tablet. In FIG. 10, additional dash-dash broken lines illustrate environment and dash-dot-dash broken lines depict boundaries. All broken lines form no part of the claimed design.
